UNITED STATES PATENT OFFICE

WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK

FLASH LIGHT

Application filed April 14, 1925. Serial No. 22,962.

This invention relates to improvements in flashlights, and more particularly to a new and improved focusing arrangement for flashlights.

5 In accordance with the present invention, the focusing of the light is controlled through the agency of a spring placed under tension between the reflector and the lamp socket between which it is located. For the purpose of 10 permitting ready assembly of the flashlight, the reflector is provided with a sufficiently large opening to permit passage of the light bulb. The socket is firmly held under spring tension between the battery and the fixed reflector, the focusing being effected by reciprocating the batteries. Rotation of the socket is prevented, preferably by means of the contact spring which connects the reflector with the switch.

20 These and other features of the invention will, however, more clearly appear from the following detailed description of a preferred embodiment thereof and the appended claims.

25 In the drawings, Fig. 1 illustrates a vertical cross-section of a flashlight embodying the present invention; Figs. 2, 3 and 4 are enlarged sectional views of the switch in its normal, intermediate and actuated positions, respectively.

30 The flashlight consists of a tubular casing 1 containing dry cells 2 surrounded by an insulating wrapper. The lowermost dry cell rests with the bottom of its zinc container electrode on the flange of a cup 3 projecting from a cap 4 which is in screw-threaded engagement with the lower open end of the casing 1. The carbon terminal 5 of the uppermost dry cell is in engagement with one terminal 6 of an incandescent electric light bulb

40 7. The other terminal of the light bulb is connected with a screw-threaded metallic sleeve or base 8 which is held in a metallic socket 9. The metallic socket has a metallic cup-shaped flange 10 resting on a disc 11 of insulating material. The disc 11 rests on a shoulder formed in the casing. The disc 11 is perforated, permitting the passage of the lamp terminal 6. The upper part of the tubular casing is formed into a bell 12 which surrounds a metallic reflector 13 insulated from

the casing by means of a sleeve 14 of suitable material. The insulation 14 rests on a shoulder formed into the bell 12. The reflector is held in place by means of a lens 15 clamped against the bell through the agency of a ring 16.

At its apex the reflector 13 is provided with an opening 17 which is large enough to permit the passage of the light bulb, and the reflector is spaced from the supporting socket of the lamp 10 by means of a coiled spring 18, the lower end of which lies within the cup 10 and the upper end of which surrounds a skirt 19 depending from the reflector 13. The spring 18 serves for three purposes; it maintains the terminal 6 of the lamp in firm contact with the carbon terminal 5 of the battery; it absorbs shocks that may otherwise cause the destruction of the lamp filament when a blow is struck near the lens end of the flashlight; and it acts as a means for permitting focusing of the flashlight. By turning the cap 4 and thus moving the batteries up or down, the lamp 7 is also moved up or down with respect to the reflector 13 against or with the tension of spring 18, accomplishing thus any desired focusing. By providing the reflector with a sufficiently large opening the flashlight may be assembled by placing the assembled bulb, socket and coiled spring 18 on top of the battery 2, and then seating the reflector with its opening surrounding the bulb.

The circuit of the lamp is closed through 8, 9, 18, the reflector 13, a flat spring 20, the free end of which is in permanent engagement with the reflector, a metallic slider 21, casing 1, cap 4, 3, and back through the battery to the other terminal of the light. Through a portion of its length the spring 20 is surrounded by insulation 32, and it is fastened to casing 1 by means of rivets 33, 34 which, however, do not make electrical contact with the spring. The spring 20 passes through a notch 31 in the disc 11 and serves thus for the purpose of preventing rotation of the latter.

The switch structure is illustrated more in detail in Figs. 2, 3 and 4. It consists of a slider 21 from which a button 22 projects through a slot 23 in the casing 1, said button

holding a corrugated piece of insulation 24. By means of its bent end 25, the spring 20 presses the slider against the inner surface of the casing 1, the contact between the slider and the casing being established by means of a wiper 26 riveted to the upper end of the slider 21 by means of a rivet 27 of insulating material. In the position of the switch illustrated in Fig. 2, wherein the spring end 25 lies in a corrugation 28 and the insulating lug 27 engages the free end of the spring 20 just below a perforation 29, depression of the button 22 will not result in the completion of the lamp circuit. When, however, the slider 21 is moved into its intermediate position, in which the spring end 25 lies within a corrugation 30, the insulating lug 27 being opposite the perforation 29, will permit engagement between the free end of spring 20 and the conducting slider 21, completing thus the lamp circuit whenever the button 22 is pressed against the tension of spring 20. If it is desired permanently to light the lamp, the slider is pushed into the position illustrated in Fig. 4, in which permanent contact is established between the spring 20 and the slider 21 and therefore with the casing 1. The switch is held in this advanced position by the spring end 25.

30. What I claim is:

1. In a flashlight, a tubular metallic casing, a flaring head for said casing, a metallic reflector held within said head and insulated therefrom, a battery of dry cells within said casing, an incandescent electric light bulb adapted to pass through an opening provided at the apex of said reflector, a disc of insulation, a metallic socket carried by said disc, the base of said bulb being in engagement with said socket and one terminal of the bulb projecting through said socket and disc into contact with one electrode of a dry cell, a metallic cup laterally projecting from said socket and carried by said disc, a coiled spring between said cup and the bottom of said reflector, a screw-threaded cap cooperating with the other end of said casing for vertically displacing said cells, socket and bulb against the tension of said spring, a switch for controlling the circuit of said bulb, and a contact spring fastened to said casing and cooperating at one end with said switch and contacting at its other end with said reflector, said contact spring serving also to hold said disc against rotation.

2. In a flashlight, a casing, a battery in said casing, an electric light bulb connected with said battery, a reflector in said casing, a socket for the base of said bulb between said reflector and battery adapted to axial adjustment, a contact spring for controlling the circuit of said bulb, and means including said contact spring for holding said socket against rotation.

3. In a flashlight, a casing, a battery in said casing, an electric light bulb connected with said battery, a reflector in said casing, a socket for the base of said bulb between said reflector and bulb, a spring placed under tension between said socket and said reflector, means for vertically moving said socket and bulb with respect to said reflector and against the tension of said spring to focus the light, a contact spring for controlling the circuit of said bulb, and means including said contact spring for holding said socket against rotation.

In testimony whereof, I have signed my name to this specification, this 9th day of April, 1925.

WILLIAM F. HENDRY.
